BOILER

John Ross Wade, San Francisco, Calif.

Application August 8, 1933, Serial No. 684,254

4 Claims. (Cl. 122—356)

The present invention relates to improvements in boilers, and its principal object is to provide a boiler for generating steam of high or low pressure, or for hot water heating systems, that is comparatively simple in construction, easy to assemble and to take apart for cleaning purposes and for repairs, and that is particularly efficient in operation and safe and durable.

A further object of the present invention is to arrange a plurality of tiers of tubes relative to the source of heat in such a manner that the products of combustion from the source of heat pass around and between the tubes of different tiers for heating water circulating therethrough.

A further object of the invention is to provide chests for water and steam at opposite ends of the tubes for causing circulation of the water or steam through the tubes and to provide structural features allowing of easy assembling and dis-

assembling, and of ready access to the tubes for cleaning and repair purposes.

A further object of the invention is to provide partitions in the chests for causing the water and steam to circulate, the partitions being arranged in such a manner as to provide direct communication with the bottom of the chests formed by the partitions.

Further objects and advantages of my invention will appear as the specification proceeds.

The preferred form of the invention is illustrated in the accompanying drawings, in which

Figure 1 shows a front view of the boiler;

Figure 2 a vertical section taken along line 2—2 of Figure 1; and

Figure 3 a transverse vertical section taken along line 3—3 of Figure 2.

While I have shown only the preferred form of the invention, I wish to have it understood that various changes or modifications may be made within the scope of the claims hereto attached without departing from the spirit of the invention.

In its preferred form the boiler comprises two spaced plates 1 and 2 interconnected by a plurality of tiers of tubes 3 open at the ends. The tubes of one tier are arranged in staggered relation to those of the adjacent tiers as shown in Figure 3, and the tubes of each tier are spaced from one another, the spacing between the tubes of each tier being arranged in such a manner that the over-all space available for the circulation of products of combustion between the tubes gradually decreases from the bottom toward the top so as to substantially correspond to the decreasing volume of the products of combustion due to heat losses. This gradual decrease in the total

available space for the circulation of the products may be brought about in different ways, as for instance by decreasing the spacing between the tiers from the bottom toward the top, or by decreasing the space between the individual tubes of each tier from bottom to top, by slightly increasing the diameter of the tube from bottom to top, by the use of smaller tubes such as indicated at 4 which may be increased in diameter from bottom to top, or by tapering the surrounding 10 housing or combustion chamber.

The two plates 1 and 2 are supported on four legs 5 and front and rear plates 6 and 7 are secured to the legs to form extensions of the plates 1 and 2 and reaching to the floor or other supporting surface for the boiler. The front plate 6 is provided with a removable door 8 through which the burner 9 with its Venturi tube 10 may be inserted, the burner resting on an angle iron 11 secured to the rear wall 7 and the Venturi tube finding additional support in an angle iron 12 secured to the front wall 6. A bottom plate 13 is supported in spaced relation to the floor by means of flanges 14 secured to the front and rear walls and forms a closure against the floor.

For circulating water through the tubes I provide a chest 15 opposite each of the plates 1 and 2, each chest being made up of a plate 16 spaced from the plate 1 or 2 respectively by means of a wall 17 and held to the plate 1 or 2 by means of 30 stud bolts 18. Within each of the two chests I provide a number of partitions 19 to direct the flow of the water back and forth through the tubes in the direction of the arrows shown in Figure 2. Water is introduced into one of the lowermost 35 chest sections through the intake pipe 20, and steam leaves through the outlet 21. The partitions 19 as indicated in Figure 1 do not all completely separate one chest section from the other, but the lowermost partition 19 is made to provide 40 a restricted communication between the first chest section 22 and the second chest section 23 as indicated at 24, while the second partition 19 also provides a restricted communication 25 between the third chest section 26 and the lowermost 45 chest section 22. This direct communication between the first section of the chest and the second section, and between the third section of the chest and the first section serves the purpose of allowing water from the second and third sections to separate from steam formed in those sections and to return to the first section while the steam advances in regular circulation through the tube.

The two plates 1 and 2 are interconnected by a

shell 27 which surrounds all the tubes and the burner, and thus forms with the plates a closed combustion chamber through which all the products of combustion have to rise in heat exchange relation with the tubes to be finally discharged through the stack 28. The shell 27 presents straight vertical side walls 29, the upper ends of which taper inwardly as shown at 30 and are connected by a horizontal top 31. The taper 30 of the shell may be used for decreasing the overall space available for the passing of the products of combustion in the manner previously described. Toward the bottom the vertical walls 29 of the shell taper inwardly as at 32 to extend within close proximity of the burner indicated at 9. The walls are preferably lined with refractory material indicated at 33.

The first shell 27 is surrounded by a second shell 34 fastened to the edges of the plates 1 and 2 and spaced from the first shell so as to form a conduit 35 therewith on each side of the boiler. The conduit is divided into two sections by a partition 36 extending substantially midway through the conduit from a point 35 a slight distance from the center line of the boiler through the inclined section of the conduit to a point 37 at the upper end of the vertical portion of the conduit. At this point the partition has hinged thereto a swingable partition 38 which extends substantially to the bottom of the conduit, paralleling in one position the inner shell 27. This swingable partition, however, may be adjusted by means of a handle 39 pivoted to the swingable partition as at 40, and adapted to be secured in adjusted position by means of a bolt 41 passing through a slot 42 of the handle and adapted to be tightened by means of a wing nut 43. A flexible sheet of asbestos cloth 43' is attached to the inner surface of wall 34 and to the outer surface of wall 38 to prevent air from passing around the bottom of the wall 38.

Air may be admitted into the conduit through a series of holes 44 in the outer shell 34 and an elongated aperture 45 in a small auxiliary housing 46 paralleling the lower portion of the boiler.

It will be noted from the arrows in Figure 3 that air enters from the outside through the elongated aperture 45, then passes through the openings 44 in the outer shell into the outer section of the conduit through which it passes upwardly in heat exchange relation with the partition 38 and 36, whereupon it turns around the upper edge of the partition and descends downwardly through the inner section of the conduit until it is finally discharged toward the source of heat. The flexible sheets 43' cause the air to take this path. It will be understood that the shell 27 naturally will be hotter than the partitions 38 and 36, so that the air, while rising through the outer chamber, will absorb some heat from the partitions 38 and 36, and on return through the inner section of the conduit will absorb further heat units from the heated wall of the inner shell. During this process the air gradually heats to a desired temperature while passing through the conduit, and the heated air expands in volume the closer it comes to the source of heat. It is desirable to arrange the cross-sectional area of the conduit so that it increases from one end to the other to correspond substantially to the increase in the volume of the air due to absorption of heat units and to accomplish the object I provide the adjustable partition. When the partition 38 is swung to the left as seen in Figure 3 and fastened in such position, the entrance to the outer section of the conduit is narrow and the cross-section increases

gradually toward the point 31. The cross-section will remain substantially the same in that portion of the conduit above the point 31 but going down from this point the cross-section will again gradually increase until the air is finally discharged at the source of heat so that as a whole the two sections of the conduit provide a gradual increase in cross-section from one end to the other and corresponding substantially to the increase in volume of the air.

The advantages of the outlined construction will be readily understood. The air is pre-heated before reaching the source of heat and the flow of the air is regulated to be substantially uniform by means of the swingable partition 38. On the other hand the spacing between the circulation tubes is decreased from bottom to top to correspond to the decrease in volume of the products of combustion due to loss of heat units so that in the entire system the fluid passages are substantially adjusted to correspond to the requirements of the fluid for insuring a uniform flow through the entire boiler from the outside atmosphere to the stack through which the products of combustion are eventually discharged. This results in a low stack temperature.

The water circulation through the tubes and the chests is arranged to proceed rapidly which causes a quick heating of the water and reduces scale formation. Any scale that is formed will find its way into the chests from which it may be easily removed. A certain amount of water can enter directly from one of the sections of the chest into the other through the respective passages 24 and 25, whereby certain differences in temperature may be equalized.

The plates 15 may be easily removed and with these plates removed easy access may be had to the tubes for cleaning purposes.

A suitable water gauge not shown may be supported between the pipes 47 and 48, a steam gauge may be attached to the pipe 49, a blow-off pipe may be provided at 50, and if the steam, after having been used is to be returned to the boiler in the form of condensed water, it may be reintroduced through the feed pipe 51. A safety valve 52 connects with the top of the back chest.

I claim:

1. In a boiler, two plates, a plurality of tubes connecting the same and supporting them in spaced and parallel relation, a shell connecting the plates so as to form a combustion chamber therewith, a source of heat in the combustion chamber below the tubes, a stack for the chamber, header plates on opposite sides of each of the first plates, a wall spacing each header plate from its companion plate so as to form a chest at opposite ends of the combustion chamber, means for admitting water into one of the chests and partitions in the steam chests arranged to provide a vertical series of chest sections at each end and to cause water to circulate in a tortuous passage through the tubes, the partitions being arranged to provide for restricted direct communication between upper and lower chest sections.

2. In a boiler, a combustion chamber, a plurality of tubes arranged in vertically spaced tiers, a source of heat below the tiers, and chests at opposite ends of the tubes and having vertically spaced horizontal partitions for forming a vertical series of chest sections at each end arranged to guide water through the tiers of tubes in a circuitous path, some of the partitions having shortened edges to afford restricted communication between different sections of the same chest.

3. In a boiler, a combustion chamber, a plurality of tubes arranged in vertically spaced tiers, a source of heat below the tiers, and chests at opposite ends of the tubes and having vertically spaced horizontal partitions for forming a vertical series of chest sections at each end arranged to guide water through the tiers of tubes in a circuitous path, some of the partitions having foreshortened edges, and flanges depending from the edges for affording restricted communication between different sections of the same chest, the flanges of partitions overlying the lowermost partition being dimensioned to lead directly past intermediate chest sections to the lowermost section. 5
4. In a boiler, a combustion chamber, a plurality of tubes arranged in vertically spaced tiers, a source of heat below the tiers, and chests at opposite ends of the tubes and having vertically spaced horizontal partitions for forming a vertical series of chest sections at each end arranged to guide water through the tiers of tubes in a circuitous path, some of the partitions having foreshortened edges, and flanges depending from the edges for affording restricted communication between different sections of the same chest, the flanges of partitions overlying the lowermost partition being dimensioned to lead directly past intermediate chest sections to the lowermost section. 10

JOHN ROSS WADE.
